C. W. STARKER,
DYNAMO ELECTRIC MACHINE.
APPLICATION FILED SEPT. 10, 1914.

1,300,506.

Patented Apr. 15, 1919.

UNITED STATES PATENT OFFICE.

CHARLES W. STARKER, OF PITTSBURGH, PENNSYLVANIA, ASSIGNOR TO WESTINGHOUSE ELECTRIC AND MANUFACTURING COMPANY, A CORPORATION OF PENNSYLVANIA.

DYNAMO-ELECTRIC MACHINE.

1,300,506.

Specification of Letters Patent. Patented Apr. 15, 1919.

Application filed September 10, 1914. Serial No. 860,974.

To all whom it may concern:

Be it known that I, CHARLES W. STARKER, a subject of the Emperor of Germany, and a resident of Pittsburgh, in the county of Allegheny and State of Pennsylvania, have invented a new and useful Improvement in Dynamo-Electric Machines, of which the following is a specification.

My invention relates to dynamo-electric machines, and it has special reference to certain novel structural features of the stators of electric railway motors.

One of the objects of my invention is to provide an apparatus of the above-indicated character which shall be extremely light in weight without sacrificing the electrical operating characteristics or the mechanical strength of the machine, the parts being constructed chiefly of pressed steel.

Another object of my invention is to provide a stator for dynamo-electric machines which shall permit of readily effected variations in the cross sectional dimensions of the magnetic circuit, thus, for example, allowing the use of a standard incasing member of relatively small cross section and the variation of the cross section of the inner parts to provide machines of materially different characteristics.

A still further object of my invention is to manufacture and combine the parts of a dynamo-electric machine frame—the majority of its members being constructed of pressed-steel—as to produce a rugged, compact, light-weight and relatively inexpensive frame, more particularly in electric railway motors.

With the above ends in view, I provide a dynamo-electric machine stator construction embodying various novel features which will be hereinafter described and subsequently pointed out in the claims.

In the accompanying drawings, Figure 1 is a view, in front elevation, of the frame of a dynamo-electric machine constructed in accordance with my invention; Fig. 2 is a view in longitudinal section, taken on the line II—II of Fig. 1; Fig. 3 is a sectional view of a modification of a portion of the structure shown in Fig. 2; Fig. 4 is a plan view, with parts broken away for clearness, of a portion of the structure shown in Fig. 1, and Fig. 5 is a view, in transverse section, taken on the line IV—IV of Fig. 2.

Referring to the drawings, the structure here shown comprises a dynamo-electric machine frame member 1, an axle bracket 2 and a suspension bar 3. The frame member 1 comprises a body portion or peripheral magnetizable band 4 of relatively large cross-section, and substantially polygonal in contour, that may have a plurality of internal facial recesses 5 and openings 6 communicating therewith for suitably securing a plurality of main polar projections (not shown) to the body portion 4, a plurality of smaller recesses 7 and communicating openings 8 for securing a plurality of inter-polar projections (not shown) to the frame, in accordance with customary practice, and a longitudinally curved or indented portion 9. It will be understood that, if desired, the recesses 5 and 7 may be omitted and the polar projections may be disposed on the flat interior surfaces of the band 4. A preferably pressed-steel incasing member for the body portion 4 comprises an intermediate, substantially parallel-sided, polygonal portion 10 which fits around the body portion, and overhanging annular end portions 11 and 12 which may be suitably tapered or otherwise fashioned to inclose the commutator end and the rear end, respectively, of an armature (not shown). The end 11 may be provided with a suitable opening 11^a, and the end 12 with suitable hand openings 13, in accordance with usual practice. The centrally-disposed end openings in the incasing member of the frame that are adapted to receive suitable bearing housing members (not shown), are suitably reinforced at their edges, as by sets of rings 14 and 15 which are respectively disposed without and within the incasing member and which may be suitably secured thereto by means of rivets 16, or in any other suitable manner. The incasing member is preferably formed of two parts which may be lap-riveted to the body portion 4 by a plurality of rivets 16^a (Fig. 5), or the parts may be welded or otherwise suitably secured together. Fig. 3 shows another form of reinforcement, in which a circular angle iron member 14^a is suitably secured to the frame to inclose the edges of each end opening.

The width or thickness of the body portion or band 4 may be varied within prede-

5 determined limits, according to the dimensions of the intermediate portion 10 of the incasing member, as indicated by the dot-and-dash lines in Fig. 2, thereby allowing the use 10 of a standard size incasing member, and a variable body portion to form therewith the main magnetic circuit of the machine, the capacity and other operating characteristics of the machine being determined chiefly by the size of the body portion 4, as will be understood.

15 The axle bracket 2 is preferably of pressed-steel construction and has a centrally-located curved portion 17 that is adapted to fit within the outer surface of the curved portion 9 of the frame, and that has circular side portions 17^a for suitably inclosing a truck axle (not shown). The bracket also has a plurality of internal recesses or pockets 20 18 and a plurality of external recesses 19 adjacent thereto, the flat faces of which are provided with openings 20 that are adapted for use in connection with the fastening of a suitable axle cap to the axle bracket.

25 The axle cap just mentioned and additional accessories to the motor frame such as a gear-case supporting arm, are fully set forth and claimed in my divisional application, Serial No. 122,386, filed September 27, 30 1916.

35 In order to strengthen the construction, a reinforcing member or shoe 21 intercepts a portion of the internally-located reinforcing rings 15 and has a curved portion 22 to fit around the inner surface of the curved portion 9 of the frame. The axle bracket may be secured to the body portion 4 and to the incasing member by means of suitable rivets 18^a, which are disposed within the recesses 17 and 18, respectively, of the bracket.

40 The suspension bar 3 may be of any familiar and suitable construction and is here shown as comprising an angle bar which is suitably secured to the frame by means of 45 rivets 23 and is provided with up-turned ends 24, for purposes of convenience in installation.

45 I do not wish to be restricted to the specific structural details or arrangement of parts herein set forth, but desire that only such limitations shall be imposed as are indicated in the appended claims.

Copies of this patent may be obtained for five cents each, by addressing the "Commissioner of Patents, Washington, D. C."

I claim as my invention:

1. A dynamo-electric-machine frame comprising an incasing member of relatively thin material, and a magnetizable band of relatively thick material fitted within said incasing member and adapted to receive and support magnetizable pole pieces, the incasing member being adapted to receive and support any one of a plurality of bands of different lengths. 55

2. A dynamo-electric-machine frame comprising an inclosing casing of relatively thin material, and a magnetizable band of relatively thick material of materially less length than the incasing member and fitting closely within the same, the incasing member being adapted to receive and support any one of a plurality of bands of different 70 lengths. 65

3. A frame for dynamo-electric machines, comprising a two-part incasing member of relatively small cross-section, a magnetizable band located within said incasing member, and means for longitudinally securing together said magnetizable band and the parts of said incasing member, the arrangement of parts being such that a single incasing member is adapted to accommodate any one of several magnetizable bands of different dimensions whereby machines of different operating characteristics may employ a standard incasing member. 75 80

4. A frame for dynamo-electric machines comprising an incasing member of relatively thin material having an intermediate portion of substantially polygonal cross-section, and a magnetizable band fitted within said intermediate portion, the arrangement of parts being such that magnetizable bands of different dimensions, within the limits of the intermediate portion, may be employed in connection with incasing members of a predetermined standard size whereby machines 90 95 having different capacities or other operating characteristics may be obtained.

In testimony whereof, I have hereunto subscribed my name this 28th day of Aug. 1914.

CHARLES W. STARKER.
